CLAIM

I claim the ornamental design for a pocket-size sanitation kit, as shown and described.

DESCRIPTION

FIG. 1 is a side elevational view of a pocket-size sanitation kit, the other side being a mirror image thereof;

FIG. 2 is a front elevational view thereof;

FIG. 3 is a rear elevational view thereof;

FIG. 4 is a top plan view thereof; and,

FIG. 5 is a bottom plan view thereof.

The characteristic feature of the design resides in the combination in tonal contrast between the dark colored and visible light-blocking upper body and lower, light-transparent sample tube section.
